SQUARE

William B. Painter, Dearborn, Mich.

Application January 19, 1942, Serial No. 427,371

5 Claims. (Cl. 33—112)

This invention relates generally to squares for laying out or testing square work and refers more particularly to an improved square suitable for any mechanical work where a square could be used.

One of the essential objects of the invention is to provide a solid one-piece square of the type mentioned that is easy and inexpensive to manufacture, strong and durable, and easy to regrind.

Another object is to provide a square having a multiple edge formation for squaring purposes, preferably four edges that can be used as desired.

Another object is to provide a square wherein one or more of the squaring edges is or are ground on a radius to provide the finest possible squaring edge.

Another object is to provide a square wherein one or more of the squaring edges is or are ground flush with the adjacent side of the base.

Another object is to provide a square wherein the base thereof is of sufficient size and thickness to counterbalance the arm of the square when the latter is extended over an edge for squaring purposes.

Another object is to provide a square wherein the distance between the radius-ground edges of the inner and outer squaring edges is greater than the distance between the squaring edges at opposite sides of the square so that said inner and outer squaring edges may be radius-ground without the grinder touching or marring the side edges mentioned.

Other objects, advantages and novel details of construction of this invention will be made more apparent as this description proceeds, especially when considered in connection with the accompanying drawing, wherein:

Figure 1 is a side elevation of a square embodying my invention;

Figure 2 is an end view thereof;

Figure 3 is a sectional view taken on the line 3—3 of Figure 1;

Figure 4 is a sectional view taken on the line 4—4 of Figure 1; and

Figure 5 is a top plan view of the square.

Referring now to the drawing, A is the base and B is the arm of a square embodying my invention.

As shown, the base A and arm B are formed from one piece of metal, preferably machine steel, and are disposed at right angles to each other. Preferably the base A is relatively thick and heavy and is substantially square-shape in cross section, while the arm B is smaller and lighter and is provided throughout its length with longitudinally extending flutes 10 separated one from another by narrow fillets 11, 12, 13 and 14, respectively. The lower and top fillets

11 and 12 are ground on a common radius and, therefore, have curved or rounded edges 15 and 16, respectively, which provide the finest possible squaring edges, while the intermediate fillets 13 and 14 have flat edges 17 and 18, respectively, flush with and constituting continuations of opposite sides 19 and 20, respectively, of the base A. The distance between the edges 15 and 16 of the lower and top fillets is greater than the distance between the edges 17 and 18 of the intermediate fillets 13 and 14 so that the edges of said lower and top fillets may be ground and reground without the grinder touching the edges of the intermediate fillets. Preferably the flutes 10 upon opposite sides of the fillet 12 continue across the adjacent end of the base A as at 10' from the inner to the outer faces 21 and 22, respectively, thereof so that the fillet 12' cooperates with the fillet 12 to provide a continuous and uninterrupted squaring edge at the top of the square from the outer end 23 of the arm to the outer face 22 of the base A. Likewise, the edges 17 and 18, respectively, of the intermediate fillets 13 and 14 cooperate with the opposite sides 19 and 20 of the base to provide continuous and uninterrupted squaring edges at opposite sides of the square from the outer end 23 of the arm to the outer face 22 of the base A. The lower and top fillets 11 and 12 are disposed at 90° angles to the intermediate fillets 13 and 14 which, as just stated, are flush with the opposite sides of the base A; hence, the square is usable under various circumstances for laying out or testing square work. For example, the base A may be slid into a space between two uprights so that the fillets 13 and 14 of the arm B could be used with the base for squaring purposes, or the base A may be slid or extended over an edge of an object so that one or more fillets of the arm B may be used against an upright edge or surface of an object spaced from the first mentioned object, in which event the heavy base A on the first mentioned object serves to counterbalance the arm B. Thus, it is apparent that the square has a multiple edge formation for squaring purposes. Such a square can be resquared quickly in any modern tool room and, therefore, does not require factory service. Moreover, it can be accurately made in a variety of sizes.

What I claim as my invention is:

1. A square of the class described having a base and an arm disposed at right angles to each other, the base being substantially square-shape in cross section, the arm being provided throughout its length with four longitudinally extending flutes separated one from another by narrow fillets, two of said fillets having flat edges flush with opposite faces or sides of said base, the other two fillets being between and disposed at 90° to

the first mentioned fillets, the edges of the last mentioned fillets being spaced apart a distance greater than the distance between the flat edges of the first mentioned fillets so that the said last mentioned fillets may be reground on a radius without the grinder touching or marring the flat edges of the first mentioned fillets.

2. A one piece square of the class described having a base and an arm disposed at right angles to each other, the base being substantially rectangular in configuration, the arm being provided throughout its length with circumferentially spaced longitudinally extending transversely curved flutes separated one from another by fillets of substantially V cross section, the fillets at the top and bottom of said arm being ground on a common radius so as to have transversely curved or rounded edges, the fillets at opposite sides of said arm intermediate the fillets aforesaid having flat edges flush with and constituting continuations of opposite sides of the base, the diametric dimension between the rounded edges of the top and bottom fillets being greater than the distance between the flat edges of the intermediate fillets so that said rounded edges may be ground and reground without the grinder contacting or touching the flat edges or the intermediate fillets, opposite sides of the base being provided from the outer face of the base to the inner end of the arm with transversely extending flutes similar in configuration to the flutes in said arm and separated from each other by a transversely extending fillet similar in cross section to the top fillet of the arm, the flutes in the base being in alignment with and constituting endwise continuations of the uppermost flutes at opposite sides of the arm, so that the lower side edges of the flutes just mentioned in the base and arm collectively provide continuous and uninterrupted squaring edges along the flush edges and sides respectively of the intermediate fillets and base at opposite sides of the square from the outer end of said arm to the outer face of the base, and the fillet of the base and the top fillet of the arm being in alignment and collectively providing a continuous and uninterrupted squaring edge at the top of the square from the outer end of the arm to the outer face of the base.

3. A solid jointless square of the class described having a base and an arm disposed at right angles to each other, the base being substantially rectangular in configuration, the arm being provided throughout its length with circumferentially spaced longitudinally extending transversely curved flutes separated one from another by fillets of substantially V cross section, the fillets at opposite sides of said arm intermediate the fillets aforesaid having flat edges flush with and constituting continuations of opposite sides of the base, the diametric dimension between the rounded edges of the top and bottom fillets being greater than the distance between the flat edges of the intermediate fillets so that said rounded edges may be ground and reground without the grinder contacting or touching the flat edges of the intermediate fillets, opposite sides of the base being provided from the outer face of the base to the inner end of the arm with transversely extending flutes similar in configuration to the flutes in said arm and separated from each other by a transversely extending fillet similar in cross section to the top fillet of the arm, the flutes in the base being in alignment with and constituting endwise continuations of the uppermost flutes at opposite sides of the arm, so that the lower side edges of the flutes just mentioned in the base and arm collectively provide continuous and uninterrupted squaring edges along the flush edges and sides respectively of the intermediate fillets and base at opposite sides of the square from the outer end of said arm to the outer face of the base, and the fillet of the base and the top fillet of the arm being in alignment and collectively providing a continuous and uninterrupted squaring edge at the top of the square from the outer end of the arm to the outer face of the base.

5. A jointless square of the class described having a base and an arm disposed at right angles to each other, the base being substantially rectangular in configuration, the arm being provided throughout its length with circumferentially spaced longitudinally extending transversely curved flutes separated one from another by fillets of substantially V cross section, the fillets at the top and bottom of said arm being ground on a common radius so as to have transversely curved or rounded edges, the fillets at opposite sides of said arm intermediate the fillets aforesaid having flat edges flush with and constituting continuations of opposite sides of the base, the diametric dimension between the rounded edges of the top and bottom fillets being greater than the distance between the flat edges of the intermediate fillets so that said rounded edges may be ground and reground without the grinder contacting or touching the flat edges of the intermediate fillets, opposite sides of the base being provided from the outer face of the base to the inner end of the arm with transversely extending flutes similar in configuration to the flutes in said arm and separated from each other by a transversely extending fillet similar in cross section to the top fillet of the arm, the flutes in the base being in alignment with and constituting endwise continuations of the uppermost flutes at opposite sides of the arm, so that the lower side edges of the flutes just mentioned in the base and arm collectively provide continuous and uninterrupted squaring edges along the flush edges and sides respectively of the intermediate fillets and base at opposite sides of the square from the outer end of said arm to the outer face of the base, and the fillet of the base and the top fillet of the arm being in alignment and collectively providing a continuous and uninterrupted squaring edge at the top of the square from the outer end of the arm to the outer face of the base.

10. 4. A jointless square of the class described having a base and an arm disposed at right angles to each other, the base being substantially rectangular in configuration, the arm being provided throughout its length with circumferentially spaced longitudinally extending transversely curved flutes separated one from another by fillets of substantially V cross section, the fillets at the top and bottom of said arm being ground on a common radius so as to have transversely curved or rounded edges, the fillets at opposite sides of said arm intermediate the fillets aforesaid having flat edges flush with and constituting continuations of opposite sides of the base, opposite sides of the base being provided from the outer face of the base to the inner end of the arm with transversely extending flutes similar in configuration to the flutes in said arm and separated from each other by a transversely extending fillet similar in cross section to the top fillet of the arm, the flutes in the base being in alignment with and constituting endwise continuations of the uppermost flutes at opposite sides of the arm, so that the lower side edges of the flutes just mentioned in the base and arm collectively provide continuous and uninterrupted squaring edges along the flush edges and sides respectively of the intermediate fillets and base at opposite sides of the square from the outer end of said arm to the outer face of the base, and the fillet of the base and the top fillet of the arm being in alignment and collectively providing a continuous and uninterrupted squaring edge at the top of the square from the outer end of the arm to the outer face of the base.

15. 5. A jointless square of the class described having a base and an arm disposed at right angles to each other, the base being substantially rectangular in configuration, the arm being provided throughout its length with circumferentially spaced longitudinally extending transversely curved flutes separated one from another by fillets of substantially V cross section, the fillets at the top and bottom of said arm being ground on a common radius so as to have transversely curved or rounded edges, the fillets at opposite sides of said arm intermediate the fillets aforesaid having flat edges flush with and constituting continuations of opposite sides of the base, the diametric dimension between the rounded edges of the top and bottom fillets being greater than the distance between the flat edges of the intermediate fillets so that said rounded edges may be ground and reground without the grinder contacting or touching the flat edges of the intermediate fillets.

WILLIAM B. PAINTER.
